UNITED STATES PATENT OFFICE.

HANS LUTZ, OF NUREMBERG, AND WILHELM SCHAEFER, OF MUNICH,
GERMANY.

FURNACE.

SPECIFICATION forming part of Letters Patent No. 554,070, dated February 4, 1896.

Application filed October 1, 1894. Serial No. 524,609. (No model.)

To all whom it may concern:

Be it known that we, HANS LUTZ, of Nuremberg, and WILHELM SCHAEFER, of Munich, Bavaria, in the Empire of Germany, subjects 5 of the King of Bavaria, have invented certain new and useful Improvements in Smokeless Furnaces, of which the following is a specification.

Furnaces at present in general use require 10 great attention and intelligence on the part of the stoker to secure perfect and smokeless combustion of the fuel. The fuel being put on irregularly and the fuel being supported by grates much loss is occasioned by imperfect combustion and by the loss of small fuel 15 passing through the grates.

The object of our invention is to burn all 20 of the combustible material of the fuel without loss and in the simplest way by limiting the combustion to the surface of the fuel and preventing the escape of any fuel until it has 25 been completely exposed to the heat and air.

We will first describe our invention with 30 reference to the accompanying drawings and then point out in the claim the novel parts.

In said drawings, Figure I is a vertical sectional elevation of a furnace embodying our 35 improvements. Fig. II is a horizontal sectional view thereof, the plane of section being indicated by the dotted line II II, Fig. I.

The fuel-chamber R has at front the inclined imperforate supporting-plate P and at rear the inclined series of air-inlet tubes or channels D, the arrangement being such that 40 the chamber R is constructed downwardly, so that as the fuel flows downward and is consumed every part of it may be more perfectly subjected to the currents of air let in by the tubes or channels D.

45 The fuel is supplied to the chamber R through a feeding-door H and slides downward on the plate P, but receives air only through the tube D; and hence is consumed only on its upper surface, the flames which there develop passing into the spaces between

the said tubes and thence to the furnace-flue F.

Slag and ashes pass down and are removed by a door A from time to time, as necessary. Air is supplied to the tubes F from air-chambers B in the side walls of the furnace, which are open at C to receive air from the space E below the plate P. Thus the air which is supplied to the burning surface of the fuel is preliminarily heated. No fresh fuel is ever put 5 on the burning surface, but is first warmed as it passes thereto down the inclined plate P. The air is distributed evenly over the surface of the fuel. No material is allowed to pass through the plate P nor discharge until it has 6 been completely combusted. A valve V is placed in the front of the chamber E to regulate the supply of air to the furnace and the speed of combustion. The pipes D are very durable, as they are cooled by air passing 7 through them and are not encumbered with ashes and slag, so that the heated products of combustion circulate freely through them.

Having thus described our invention, the following is what we claim as new therein and 7 desire to secure by Letters Patent:

In a smokeless furnace, the combination of the inclined imperforate plate P, the series of parallel air-tubes D arranged in an inclined plane over the plate P and forming between 7 them and said plate a downwardly-constricted fuel passage or chamber, said tubes D having spaces or passages between them for the passage of the products of combustion and being formed with air-openings in their faces adjacent to the plate P, fuel-inlet H, the air-chamber E below said plate P, and air-passages connecting with said air-tubes, substantially 8 as set forth.

HANS LUTZ.
WILHELM SCHAEFER.
